(57) **CLAIM**

We claim the ornamental design for a faucet, as shown and described.

DESCRIPTION

FIG. 1 is a first perspective view of a faucet embodying the present invention.

FIG. 2 is a second perspective view of the faucet of FIG. 1.

FIG. 3 is a front view of the faucet of FIG. 1.

FIG. 4 is a rear view of the faucet of FIG. 1.

FIG. 5 is a first side view of the faucet of FIG. 1.

FIG. 6 is a second side view of the faucet of FIG. 1.

FIG. 7 is a top view of the faucet of FIG. 1.

FIG. 8 is a bottom view of the faucet of FIG. 1.

FIG. 9 is a first perspective view of another faucet embodying the invention.

FIG. 10 is a second perspective view of a faucet of FIG. 9.

FIG. 11 is a front view of the faucet of FIG. 9.

FIG. 12 is a rear view of the faucet of FIG. 9.

FIG. 13 is a first side view of the faucet of FIG. 9.

FIG. 14 is a second side view of the faucet of FIG. 9.

FIG. 15 is a top view of the faucet of FIG. 9; and,

FIG. 16 is a bottom view of the faucet of FIG. 9.

The present application is directed to the shape and contour of the designs illustrated in the drawings. The elements shown in broken lines form no part of the claimed design and are included for the purpose of showing the environment of the claimed design.

1 Claim, 16 Drawing Sheets
